UNITED STATES PATENT OFFICE.

CHRISTIAN KNAUER, OF PITTSBURGH, PENNSYLVANIA.

COPYING-PRESS.

Specification of Letters Patent No. 15,011, dated June 3, 1856.

To all whom it may concern:

Be it known that I, CHRISTIAN KNAUER, of Pittsburgh, in the county of Allegheny and State of Pennsylvania, have invented a new and useful Improvement in Copying-Presses; and I do hereby declare that the following, is a full, clear, and exact description of the construction and operation of the same, reference being had to the annexed drawings, making a part of this specification, in which—

Figure 1 is a perspective view; Fig. 2, a transverse vertical section; Figs. 3, 4 and 5, perspective views of detached parts.

15 In all these figures the same letters refer to like parts.

A is the bottom plate; B the frame, consisting of the cross-piece *a a* and the pillars *b, b*, fastened or cast on the bottom plate; 20 D is the top or pressure plate, which is provided with the flanges *d, d* (of which one is shown separately in Fig. 5); this plate is guided on the pillars *b b* of the frame.

C is a cam, which I call the regulating cam; it swings on the pivot *c* in the middle of the cross piece *a, a*, and is provided with a handle *e*; the cam is constructed so, that it has an outside eccentric surface *m, m*, which is toothed or roughened, and an inside surface *n, n*, which is parallel to the surface *m, m*, and smooth; the object of this construction will be shown hereafter; F is a friction-roller, whose pin *f* passes through the holes *f'* in the flanges *d*; G is another 30 cam, which is shown separately in Fig. 3, and which I call "the pressure cam;" its journals *g, g*, pass through openings (*g'*) in the flanges *d*; H is a lever set firmly on one of the journals *g*; J is an intermediate 35 cam, which is shown separately in Fig. 3, and which I call "the pressure cam;" its journals *g, g*, pass through openings (*g'*) in the flanges *d*; H is a lever set firmly on one of the journals *g*; J is an intermediate 40 block, between the pressure cam G, and the regulating cam C, which I call the "friction piece" (the same is shown separately in Fig. 4); its projections *j j* enter into the recesses *r r* in the flanges *d, d*; these recesses 45 are cut out sufficiently, to allow the friction piece to move a little up and down, so as to get into, or out of contact with the surface *m* of the regulating cam; the surface of the friction piece, which comes into contact with 50 said cam C, is also toothed or roughened, similar to the surface *m, m*. The purpose of the regulating cam is to raise or lower the top plate D, so that the space between said plate and the bottom A may be regulated 55 to suit any size or thickness of copying books. The pressure, required for the copy-

ing process, is effected by means of the pressure cam G, which is operated by its lever H.

The operation of the press is as follows: When the lever H is pressed down, the cam G presses against the friction-piece J, which, as it bears against the cam C, is prevented from yielding, causing hereby the plate D to descend or press downward; the cam C during this operation is kept from turning 65 around its pivot *c*, by its toothed surface *m m* being in contact with the toothed surface of the friction piece. When the pressure is down and the lever H is raised again the friction piece J will be released from its 70 contact with the cam C, and the friction roller by the weight of the top plate D, will come down on the inner surface *n n* of the cam C, making thus the top plate D suspended on the said cam C; in this position 75 the top plate can be raised or lowered according to the direction, in which the cam C may be turned (by means of its handle *e*); the friction roller traveling on the inner surface *n n* of the cam.

80

The manner in which the press is used, according to the described construction, is as follows: Lift the lever H, as indicated by arrow in Fig. 2; and also turn the regulating cam, as indicated by arrow at the handle 85 *e*; put then the copy book between the plates A and D, and allow the cam C to fall or turn back, whereby the plate D will descend, down on the book, then produce the pressure, by pressing the lever H down. Lift 90 now the lever H up again, and also the handle *e*, whereby the top plate is raised, so that the book can be taken out again. By letting, in this position of the press, the lever H drop down, the press plate will be 95 kept in its raised position, as the friction piece will get into contact with the surface *m, m*.

What I claim herein as new, and desire 100 to secure by Letters Patent is—

Adjusting the plates of a copying press to suit different sized books, by means of a regulating cam (C), which carries the top plate (D), so arranged, that it shall be the bearing of the pressure cam;—either directly or by the intervention of the friction piece J, substantially as described.
